CLAIM

The ornamental design for a snowmobile body panel, as shown and described.

DESCRIPTION

FIG. 1 is a rear right perspective view showing a first embodiment of a snowmobile body panel according to our design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a rear left perspective view showing a second embodiment of a snowmobile body panel according to our design;

FIG. 9 is a right side elevation view thereof;

FIG. 10 is a left side elevation view thereof;

FIG. 11 is a front elevation view thereof;

FIG. 12 is a rear elevation view thereof;

FIG. 13 is a top plan view thereof; and,

FIG. 14 is a bottom plan view thereof.

Throughout the Figures, the dashed broken lines represent environmental matter and/or unclaimed portions of the snowmobile front fairing and form no part of the claimed design. The dash-dot broken lines represent the boundary between claimed and unclaimed areas and form no part of the claimed design.

In the drawings, the broken lines depict unclaimed subject matter only and form no part of the claimed design. The dash-dot lines represent the boundary between claimed and unclaimed areas and also form no part of the claimed design.
